RIDER MERRY-GO-ROUND OR SIMILAR ARTICLE

Ronald W. Zick, Torrance, Calif., assignor to Jamison, Inc., Torrance, Calif., a corporation of California

Filed Dec. 18, 1967, Ser. No. 9,827

Term of patent 14 years

(Cl. D34—5)

FIG. 1.

FIG. 2.

FIG. 3.

FIGURE 1 is a perspective view of a rider merry-go-round or similar article showing my new design;

FIGURE 2 is a side elevational view of a rider merry-go-round or similar article showing my new design; and

FIGURE 3 is a top plan view of a rider merry-go-round or similar article showing my new design.

The side opposite that shown in FIGURE 2 is a mirror image thereof.

The broken lines indicating a mounting means are for illustrative purposes only.

I claim:

The ornamental design for a rider merry-go-round or similar article, as shown and described.
